UNITED STATES PATENT OFFICE.

GEORG E. SCHMIDMER, OF NUREMBERG, GERMANY.

PROCESS OF PRODUCING GLITTER-POUNCE.

SPECIFICATION forming part of Letters Patent No. 668,420, dated February 19, 1901.

Application filed July 11, 1900. Serial No. 23,238. (No specimens.)

To all whom it may concern:

Be it known that I, GEORG E. SCHMIDMER, a subject of the King of Bavaria, residing at Nuremberg, Bavaria, Germany, (whose post-office address is Schweinau, Nuremberg, Bavaria,) have invented certain new and useful Improvements in Processes of Producing Glitter-Pounce; and I do hereby declare the following to be a full, clear, and exact description of the invention, such as will enable others skilled in the art to which it appertains to make and use the same.

The object of the invention is to produce glitter-pounce of a structure and degree of fineness which have not yet been attained.

In the drawings, which represent symbolically and on exaggerated scale the consecutive stages of the process, Figure 1 comprises a side and end elevation of elements arranged according to the first step of the process. Fig. 2 represents the outline assumed in undergoing the second stage of the process, not as yet fully completed; and Figs. 3 and 4 represent, respectively, the shape imparted to the core and to the pounce upon the completion of the process.

Referring now to said figures, the first step of the process (indicated in Fig. 1) consists in spirally spinning over a wire *a* a second wire *b*, but of less diameter. The wire treated in this manner is subjected in the second act, by means of a rolling-press or such like, to a cer-

tain pressure, the direction of which is shown by arrow-marks in Figs. 1 and 2. The wire is flattened by this process and separated in 35 two halves, which have the form represented in Fig. 4. These bean-like particles *c* still lightly adhere to the wire core *a*, but are by any suitable contrivance removed from this and form the desired glitter-pounce. The 40 core-wire *a* is likewise flattened, and thus transformed into plate of strangely-indented form, Fig. 3, and can thus be advantageously used for other purposes.

Fig. 2 illustrates the change in form of the 45 prepared wire mentioned at beginning, and shows, for example, the form it takes when the pressure has nearly, but not yet completely, separated the two halves of the external wire.

What I claim, and desire to secure by Letters Patent, is—

The process for producing glitter-pounce, consisting in first spinning one wire around another and then subjecting the two wires to 55 pressure at opposite ends of a diameter through the core-wire until the coils of the external wire are divided by such pressure.

In testimony whereof I affix my signature in presence of two witnesses.

GEORG E. SCHMIDMER.
